ELEVATOR

James Dunlop, Ridgewood, N. J., assignor, by
mesne assignments, to Westinghouse Electric
Corporation, East Pittsburgh, Pa., a corpora-
tion of Pennsylvania

Application December 22, 1943, Serial No. 515,257

9 Claims. (Cl. 187—95)

1

My invention relates to elevators and, more particularly, to means for leveling the platforms of deck-edge elevators on airplane-carrier ships with the flight decks thereon.

In a typical ship of this character, the flight deck overhangs the edge of the ship about 16', and out of this overhanging part of the deck is notched a space for an elevator platform which is about 60' long and 34' wide and which weighs approximately 60 tons. The platform extends approximately 18' beyond the overhanging edge of the flight deck, and the whole platform structure is suspended by a plurality of hoisting cables between a pair of guide rails mounted on the outside of the ship hull. A plurality of guide shoes are mounted on the platform structure and disposed in slots in the guide rails for guiding the platform between the guide rails.

In an elevator of this character and this size, it is important that the platform should stay level and flush with the flight deck when it is parked thereat, so that the arrestor hooks on the airplanes landing on the flight deck will pass safely over the platform and the adjacent edges of the flight deck without being caught. Therefore, one object of my invention is to provide for leveling an elevator platform with its landing and maintaining it in level condition therewith regardless of the position of any load on the platform.

Another object is to provide a leveling means for a ship elevator platform having a two point lift which will cause it to stay level with the upper deck of the ship regardless of any conditions to which it may be subjected.

For a better understanding of the invention, reference is made to the accompanying drawings, in which,

Figure 1 is a view in side elevation of a deck edge elevator looking outboard from the inside of the ship with the guide rails in cross section;

Fig. 2 is a top plan view of the elevator platform illustrated in Fig. 1, with parts of the flight deck and the elevator platform broken away to reduce the size of the drawing;

Fig. 3 is a view taken on the line III—III of Fig. 2;

Fig. 4 is a view taken on the line IV—IV of Fig. 2;

Fig. 5 is an enlarged top-plan view of one of the guide shoes in its guide rail;

Fig. 6 is a view taken on the line VI—VI of Fig. 1, illustrating the end roller in one of the guide shoes, and

Fig. 7 is a view taken on the lines VII—VII of Fig. 6.

2

Although the invention is illustrated and described in connection with a deck edge elevator and the main measurements of such an elevator now in use are many, it may be used with different sizes of platforms and with platforms of other types of elevators.

Referring more specifically to the drawings, I have illustrated a deck edge elevator having a platform 10 disposed between a pair of guide rails 11 and 12 mounted on the outside of a ship hull 13 (only a small portion of which is shown) in position to be supported by and to be raised and lowered between a main deck (not shown) and a flight deck 15 by a plurality of hoisting cables 16 and 17 attached to its fore and aft ends by hitches 18 and 19. The hoisting cables may be operated by any suitable means, such as a hydraulic engine like that illustrated and described in my co-pending application Serial No. 515,992, filed December 28, 1943, and assigned to the Westinghouse Electric Elevator Company.

The platform 10 may be constructed of seamless steel tubing, structural steel sections and steel plate welded together in bridge-like form to form a relatively light but strong structure 20.

The guide rails 11 and 12 are provided with channeled faces 21 and 22 facing each other and are mounted on backing plates 23 and 24. The backing plates are secured to the ship hull by a plurality of horizontal brackets 25 which are welded thereto to provide a strong support for the guide rails.

The platform is guided in the guide rails by four roller type guide shoes 27, 28, 29 and 30. The guide shoes 27 and 29 are mounted one above the other on the aft end of the platform for engaging the channel 21 in the guide rail 11. The guide shoes 28 and 30 are mounted one above the other on the fore end of the platform in position to engage the channel 22 in the guide rail 12.

Referring to Figs. 5 and 6, the guide shoe 27 comprises a cast metal body 32 and a side roller 33 and an end roller 34 mounted therein. The guide shoe body 32 is securely fastened to the platform framework 20 by a plurality of bolts 35. The side roller 33 is mounted on a shaft 36 which is rotatably mounted in the upper cylindrical portion 37 of the body 32, so that it will bear against either a renewable steel strip 38 or a renewable steel strip 39 mounted on the side-walls of the channel in the guide rail 11 to prevent lateral movement of the platform.

The guide roller 34 is disposed to engage the inner face of the channel 21 to prevent end movement of the platform and is rotatably mounted

on a pin 41 disposed in the forked end of a round shaft 42, slidably disposed in the lower cylindrical portion 43 of the body 32. The end roller 34 is biased into engagement with the inner face of the channel 21 by a coiled compression spring 45 disposed between the central face of a cavity 50 in the rear-end of the roller shaft and the inner face of a cap 46, which is mounted on the cylinder 43 by a plurality of bolts 47. The spring is selected with a steep characteristic to balance the weight of the platform. The shaft 42 is prevented from rotating in the body 32 by a pair of fins 49 on the inner side of the cap 46 which extend into slots 48 in the rear end of the shaft, so that the end roller 34 will always track in a vertical direction in the channel 21. The holes in the cap 46 for the bolts 47 are made loose so that the cap may be rotated slightly to aline the roller with its guide rail before the bolts are tightened.

A pair of bolts 51 and 52 pass loosely through the cap 46 and screw into the rear-end of the shaft 42. These bolts are used only during assembly to hold the spring compressed until the platform is properly alined in the guide rails. After the platform is correctly positioned the bolts 51 and 52 are removed and watertight plugs are inserted in the holes. Thus the spring is free to bias the roller against the guide rail at all times. A rearwardly extending central projection 54 is disposed on the rear-end of the shaft 42 to provide a means for limiting the rearward movement of the shaft when the spring 45 is compressed by movement of the platform toward the guide rail.

A hardened steel striking bar 56 is mounted on the rear-end of the projection 54 by a press fit and a pin 55 in position for engaging a "stop" or bending bar 58. The "stop" bar is disposed across a pair of shoulders 59 at the ends of a rectangular depression 60 in the inner side of the cap 46 and is held in position by brass screws 58a which pass through its ends into the cap 46. The end of the striking bar is rectangular in shape facing the central portion of this bending bar. When the force exerted by the platform on the guide shoe exceeds a predetermined amount, the striking bar will engage the bending bar and bend it into the space 60, thus relieving the strain on the end roller when it exceeds the normal amount for which it is designed. The platform guide rails and guide shoes are usually so designed that, under normal conditions, a space 61 measuring one-eighth inch exists between the striking bar 56 and the bending bar 58 to permit that much spring biased play of the roller 34 during normal operation. The bending bar 58 is so selected as to size and strength that it will bend and permit the end roller 34 to compress the spring 45 more than one-eighth inch only when a predetermined dangerous pressure tends to move the platform endways. The end of the striking bar 56 is rectangular in shape and fits loosely into a rectangular depression in the cap 46. A slipper block 57 (Fig. 5) is mounted on each end of the platform in position to engage the backing plate 24 and prevent further endwise movement of the platform in case it forces the bending bar to its bending limit. The end of the striking bar 56 is rectangular in shape and fits loosely into a rectangular depression in cap 46. The bending bar and the slipper block construction are illustrated, described and claimed in the pending application Serial No. 516,046, filed December 29, 1943, and assigned to the Westinghouse Electric Elevator Company.

The guide shoes 28, 29 and 30 and the slipper blocks associated therewith are constructed in the same manner and are mounted on the elevator platform in the same manner as the guide shoe 27 and the slipper block 57 except that the guide shoes 29 and 30 are mounted in what may be called an upside down relation to the guide shoes 27 and 28.

A plurality of locks 65, 66, 67 and 68 (Figs. 2, 3 and 4) are provided for locking the platform against the flight deck when it is to remain out of normal operation for any length of time. The lock 65 comprises a cast body 70 which is securely fastened to the underside of the flight deck 15, a lock bolt 71 slidably disposed in the casting and a stop member 72 mounted on the adjacent end of the platform. The side of the casting 70 adjacent the platform has a downwardly and inwardly sloping face or beveled surface 73 disposed to be engaged by an outwardly and downwardly sloping or beveled face 74 on the stop member 72 when the platform is raised to the flight deck. The beveled faces 73 and 74 cooperate to stop and center the platform at the flight deck.

The lock bolt 71 is provided with an outwardly and downwardly sloping or beveled face 75 for engaging an upwardly and outwardly sloping face 76 on the angular stop member 72 when in locking position. The rear-end of the lock bolt is connected to an operating rod 78 by a link 79 and a lever arm 80, so that rotative movement of the rod 78 will move the lock bolt into or out of its locking position. The lock 66 is constructed in the same manner as the lock 65.

The lock 67 comprises a casting 82 fastened to the underside of the flight deck, a lock bolt 83 slidably disposed in the casting 82 and a stop member 84 mounted on the adjacent end of the platform. The rear-end of the lock bolt 83 is connected by a link 85 and a lever arm 86 to the locking rod 78, so that it will be moved into and out of locking position with the lock bolt 71. The engaging surfaces of the bolt 83, the stop 84 and the casting 82 are horizontally disposed so that they will prevent vertical movement of the platform when the lock bolt is in locking position but may permit a limited horizontal movement of the platform. The lock 68 is constructed in the same manner as the lock 67. The locks are described and claimed in the pending application Serial No. 514,520, filed December 16, 1943.

It is important that the platform shall lie level with the flight deck when it is moved thereto and, in order to insure this position of the platform, I have provided a cam 100 for engaging the roller 34 at the aft end of the elevator and a cam 101 for engaging the roller 34a at the fore end of the elevator as the platform rides up to its position level to the flight deck. The cam 100 is removably mounted on the inner face of the channel 21 at a point where its upper thickest portion will be engaged by the end wheel 34 and the cam 101 is mounted on the interface of the channel 22 where its upper thickest end will be engaged by the end wheel 34a when the platform is flush with the flight deck. The distance the cams extend outwardly from the inner face of the channels may be adjusted by the use of suitable shims between the cams and the channels.

The cams cooperate with the guide shoe rollers 34 and 34a, the beveled faces 73 and 74 at the aft end of the platform, the beveled faces 73a and 74a on the lock 66 at the fore end of the platform,

and with the hoisting cables to level the platform flush with the flight deck. The hoisting cables are set to have a stretch in them equal to the weight of the platform, plus the total live load at both ends of the platform, when the platform is stopped at the flight deck.

The stretch is obtained by placing stops on the flight deck to stop the platform and by placing stops on the hoisting engine plunger at such position that the engine will continue the hoisting pull on the cables after the platform is stopped at the flight deck until all of the stretch in the cables is taken up, as is described and claimed in my copending application Serial No. 507,132, filed October 21, 1943.

As stated before, the end wheels 34 and 34a may compress their springs a distance equal to one-eighth of an inch. The cams extend outwardly from the channel faces approximately one-eighth of an inch. Therefore, when the platform is brought flush with the flight deck, the end wheels 34 and 34a roll upon the cams and are moved inwardly to take up their one-eighth inch clearance and in this position they center the platform firmly between the beveled edges 73 and 73a on the flight deck.

An assumed operation of the elevator

It will be assumed that the platform has been lowered below the flight deck and is now being returned to the flight deck by the hoisting cables 16 and 17. As the platform moves upwardly from its lower position and nears its flight deck position, the end rollers 34 and 34a roll upon the lower ends of the cams 100 and 101 and are thereby moved inwardly against the biasing effect of their compression springs. As the platform continues its upward movement, the increasing thickness of the cams continues forcing the end rollers inwardly. The compression of the springs forces the platform into its central position with reference to the beveled faces on the locks 65 and 66 and, as the platform reaches its final position, the cams force the rollers 34 and 34a inwardly until the clearance back of them is completely taken up and the platform is then in a true central position with reference to the beveled faces on the locks 65 and 66.

If the load on the platform is unevenly balanced by being placed at the fore end of the platform, the platform may be lower at its fore end than it is at its aft end. In such a case, the platform will pivot on its end roller 34 as the beveled face 74 engages the beveled face 73 and the fore end of the platform will swing upwardly into place under the pressure of the cables, until the beveled faces 73a and 74a at the fore end of the platform, so that the platform will now lie flush with the flight deck and will remain in that position, because the hoisting cables are at the limit of the stretch for which they are designed, the platform is in true center position between the cams and the beveled faces on the platform are in contact with the beveled faces on the flight deck.

By the foregoing description it will be seen that I have provided a means for leveling a long elevator platform at a flight deck which will bring it flush with the flight deck under all conditions of loading, and which maintain it flush with that deck under any condition of load.

Although I have illustrated and described only one specific embodiment of my invention, many changes therein and modifications thereof may be

made without departing from its spirit and scope.

I claim as my invention:

1. In an elevator for serving an upper floor, a pair of guide rails, a platform disposed between the guide rails, a stop device on the floor for each end of the platform, each stop device having a downwardly and inwardly sloping face, a stop device mounted on each end of the platform, each of said stop devices having an outwardly and downwardly sloping face for engaging the corresponding stop device on the floor, a cable at each end of the platform for operating the platform and pulling it up against the floor to a point where the sloping faced stop devices on the platform engage the sloping faced stop devices on the floor, and means disposed on the guide rails for centering the platform with the stop devices at the floor as the platform arrives thereat.
2. In an elevator for serving an upper floor, a pair of guide rails, a platform disposed between the guide rails, a cable at each end of the platform for operating the platform, a guide roller movably mounted on each end of the platform in position to engage the guide rail thereat for guiding the platform between the guide rails, means for biasing each guide roller toward its associated guide rail, means for limiting the rearward movement of each guide roller to a predetermined distance, a stop device mounted on the parking floor for each end of the platform, each of said stop devices having an inwardly and downwardly sloping face, a stop device mounted on each end of the platform, each of said stop devices having an outwardly and downwardly sloping face disposed to engage the sloping faces on the stop devices mounted on the floor when the platform arrives at the floor, and a cam disposed in each guide rail for engaging the guide roller associated therewith as the platform arrives at the parking floor to force the guide rollers to their rearward limit and thereby center the platform with its stop devices between the sloping faces of the stop devices on the floor.
3. In an elevator for serving an upper floor, a pair of guide rails, a platform disposed between the guide rails, a cable at each end of the platform for operating the platform, an upper guide roller and a lower guide roller movably mounted on each end of the platform in position to engage the guide rail thereat for guiding the platform between the guide rails, means for biasing each guide roller toward its associated guide rail, means for limiting the rearward movement of each guide roller to a predetermined distance, a stop device mounted on the parking floor for each end of the platform, each of said stop devices having an inwardly and downwardly sloping face, a stop device mounted on each end of the platform, each of said stop devices having an outwardly and downwardly sloping face disposed to engage the sloping faces on the stop devices mounted on the floor when the platform arrives at the floor, and a cam disposed in each guide rail for engaging the upper guide roller associated therewith as the platform arrives at the parking floor to force the guide rollers to their rearward limit and thereby center the platform with its stop devices between the sloping faces of the stop devices on the floor.
4. In an elevator for serving a parking floor, a pair of guide rails, a platform disposed between the guide rails, a cable at each end of the plat-

form for supporting, raising and lowering the platform, an upper and a lower guide roller movably mounted on each end of the platform in position to engage the guide rail thereat for guiding the platform between the guide rails, means for biasing each guide roller toward its guide rail, means for limiting the rearward movement of each guide roller to a predetermined distance, a beveled stop device mounted on the parking floor for each end of the platform for stopping it at the parking floor, and a cam disposed in each guide rail for engaging the upper guide roller associated therewith as the platform arrives at the parking floor to force said upper guide rollers to their rearward limit and thereby center the platform with the beveled stops.

5. In an elevator for serving a parking floor, a pair of guide rails, a platform disposed between the guide rails, a cable at each end of the platform for supporting, raising and lowering the platform, a guide movably mounted on each end of the platform in position to engage the guide rail thereat for guiding the platform between the guide rails, means for biasing each guide toward its guide rail, means for limiting the rearward movement of each guide to a predetermined distance, a beveled stop device mounted on the parking floor for each end of the platform for stopping it at the parking floor, and a cam disposed in each guide rail for engaging the guides as the platform arrives at the parking floor to force said guides to their rearward limit and thereby center the platform with the beveled stops.

6. In an elevator for serving a parking floor, a pair of guide rails, a platform disposed between the guide rails, a cable at each end of the platform for supporting, raising and lowering the platform, said cables having a stretch in them equal to the weight of the platform plus the total live load at both ends of the platform, an upper and a lower guide movably mounted on each end of the platform in position to engage the guide rail thereat for guiding the platform between the guide rails, means for biasing each guide toward its guide rail, means for limiting the rearward movement of each guide to a predetermined distance, a beveled stop device mounted on the parking floor for each end of the platform for stopping it at the parking floor, and a cam disposed in each guide rail for engaging the upper guides as the platform arrives at the parking floor to force said upper guides to their rearward limit and thereby center the platform with the beveled stops.

7. In a deck edge elevator for serving a deck on a ship, a pair of guide rails, a platform disposed between the guide rails, a pair of cables for operating the platform, an upper and a lower guide shoe mounted on each end of the plat-

5 10 15 20 25 30 35 40 45 50 55 60

form, a roller mounted in each guide shoe to engage the associated guide rail for guiding the platform along it, means for biasing each roller toward its guide rail, a block mounted in each guide shoe for limiting the rearward movement of its roller to a predetermined distance, a beveled stop device at each end of the platform for stopping it at the deck, and a cam disposed on each guide rail, each of said cams having its thin end disposed downwardly along its guide rail and its thick end disposed at the point where the roller on the upper guide shoe roller rests when the platform is at the deck, said thick end of each cam being approximately equal in thickness with the predetermined limited rearward movement of the rollers.

8. In a deck edge elevator for serving a flight deck on a ship, a pair of guide rails, a platform disposed between the guide rails, a cable at each end of the platform for supporting, raising and lowering the platform, said cables having a stretch in them equal to the weight of the platform plus the total live load at both ends of the platform, an upper and a lower guide shoe mounted on each end of the platform in position to engage the guide rail thereat for guiding the platform between the guide rails, each guide shoe having a roller mounted on the outer end of a shaft slidably disposed in the guide shoe, a spring disposed in each guide shoe for biasing its roller toward the guide rail adjacent thereto, a block mounted in each guide shoe for limiting rearward movement of the roller and its shaft to a predetermined distance, a beveled stop device at each end of the platform for stopping it at the flight deck, and a cam disposed in each guide rail, each of said cams having its thin end disposed downwardly along its guide rail and its thick end disposed at the point where the roller on the upper guide shoe rests when the platform is at the flight deck, said thick end of each cam being approximately equal in thickness with the predetermined limited rearward movement of the rollers.

9. In an elevator for serving a plurality of floors, a pair of guide rails, a platform disposed between the guide rails, a plurality of cables for operating the platform, a guide movably mounted on each end of the platform in position to engage the guide rail thereat for guiding the platform between the guide rails, springs disposed between the guides and the platform for centralizing the platform between the guide rails, means for limiting the rearward movement of each guide to a predetermined distance, and cams disposed on the guide rails for engaging the guides and forcing them to their rearward limit as the platform arrives at a selected floor to positively centralize the platform at that floor.

JAMES DUNLOP.
